ATTORNEY

UNITED STATES PATENT OFFICE.

EMIL KOENIG, OF NEW YORK, N. Y., ASSIGNOR TO DANIEL KOPS, ROBERT LAMBERT, HENRY V. LAMBERT, AND AUGUST V. LAMBERT.

LOCKING-LATCH.

SPECIFICATION forming part of Letters Patent No. 436,761, dated September 16, 1890.

Application filed February 18, 1890. Serial No. 340,932. (No model.)

To all whom it may concern:

Be it known that I, EMIL KOENIG, a subject of the Emperor of Austria-Hungary, residing at the city of New York, in the county of New York and State of New York, have invented a new and useful Improvement in Locking-Latches, of which the following is a specification.

The nature of the invention consists in the details of combination and construction, substantially as illustrated in the accompanying drawings, hereinafter described, and subsequently pointed out in the claim.

My invention relates to that class of locking-latches commonly known as "dead-locks," and has for its object to produce a simple and inexpensive device whereby the bolt of such lock when it has been moved either forward or backward will be held firmly in position, substantially as hereinafter described and claimed.

Figure I is an edge view of my newly-invented lock. Fig. II is a sectional view of the same, taken on a line parallel to the parting-plate and illustrating the interior of my said lock. Figs. III and IV are detail views showing the operation of the bolt. Fig. V is a sectional view of the escutcheon-tube. Fig. VI is a detail view of the turning-post and its eccentric.

In the several figures, *a* designates the escutcheon-tube, *b* the casing of the lock, and *c c'* the bolt. The front end of the bolt is beveled in the usual way at *c'*. The back end of the bolt is formed with two branches, designated, respectively, by *e* and *e'*. This bolt slides in the casing in the common and well-known way. The turning-post *i n*, which extends on either side without the casing and is supported thereby, stands in the space between the tines *e e'* of the bolt. The stop *i'* and the eccentric *i''* are carried by this post and work against the pins *h* and *h'*, which are fastened in the top sides of said tines *e e'* of the bolt, the said stop and eccentric extending over the top side of said tines far enough to engage said pins. A helical spring *o*, extending between the pins *o'* and *e'*, assists

the motion of the bolt. The escutcheon-tube, which is of the usual form, is adapted to cover 50 the upper end of the post *i*, and is provided with a warding-pin *a'*.

The key may be of any convenient form; but I prefer to use a flat key, which, passing down through the escutcheon-tube *a*, has a 55 notch cut in its edge corresponding to the pin *a'*, and has its end adapted to a slot in the upper end of the post *i*. If the post *i* and the cam *i''* be turned from the position illustrated in Fig. IV to that illustrated in Fig. 60 II, the corner of the cam impinging upon the pin *h'* will force the bolt backward. When the bolt has moved far enough backward, the corner of the cam will pass the pin *h'*, the stop *i'* come against the pin *h*, and the parts 65 take the position illustrated in Fig. III, and the bolt will be firmly held in that position. If the post *i* be turned in the opposite direction, the cam *i''* moves away from the pin *h'* toward the pin *h* and the stop *i'* from the pin *h* toward the pin *h'*. As soon as the bolt is 70 released the elasticity of the spring *o* causes it to spring forward into a locked position. Then if the motion of the post last described be further continued the parts will assume 75 the position illustrated in Fig. IV and the bolt will be held firmly in locked position. The post *i* may be turned from the escutcheon side by a key, which may be as hereinbefore described; or a convenient knob may be 80 mounted on the tine *n*, by which it may be turned from the opposite side.

Otherwise than as herein described my invention may be used as other locks of its class.

What I claim as my invention, and desire to secure by Letters Patent, is—

The combination, with the casing and bolt of a lock, said bolt being formed with branches, as specified, of a revoluble post 90 mounted in said casing between said branches, a stop and a cam carried by said post and reaching over said branches of said bolt, means, substantially as specified, for turning said post, pins upon the upper sides of the 95 branches of said bolt and adapted for engag-

ing said stop and cam above the branches of
said bolt, and a spring attached to said bolt
and said casing to assist the motion of said
bolt, all substantially as and for the purpose
5 set forth.

In testimony that I claim the foregoing as
my invention I hereto set my hand, in pres-

ence of two witnesses, this 14th day of Janu-
ary, 1890.

EMIL KOENIG.
